UNITED STATES PATENT OFFICE.

ADOLPH G. KAUFMAN AND LEOPOLD J. LIPPMANN, OF NEW YORK, N. Y., ASSIGNEES
TO AMERICAN CALLAPHONE COMPANY, OF NEW YORK, N. Y., A CORPORATION OF
GEORGIA.

TELEPHONE.

No. 921,119.

Specification of Letters Patent.

Patented May 11, 1909.

Application filed November 13, 1906. Serial No. 343,198.

To all whom it may concern:

Be it known that we, ADOLPH G. KAUFMAN and LEOPOLD J. LIPPMANN, both citizens of the United States, and residents of the borough of Manhattan, city, county, and State of New York, have jointly invented certain new and useful Improvements in Telephones, of which the following is a specification.

10 Our invention relates to electric telephones and has for its object, first, to improve the arrangement of the transmitter so as to secure the greatest efficiency and also to enable a plurality of receivers to reproduce the same sound simultaneously at different places; second, to provide an arrangement by which telephones of the usual type may be combined conveniently with our loud-speaking telephones; third, to provide improved means for giving signals, preparatory to speaking over the telephone, and fourth, to provide various improvements in construction, as will be fully described herein-after, and particularly pointed out in the appended claim.

Reference is to be had to the accompanying drawings, in which—

Figure 1 is a front elevation of a transmitter station constructed according to our invention; and Fig. 2 is a diagram showing the arrangement of circuits for the apparatuses.

We will first describe the construction of the transmitter station, particularly with reference to Fig. 1. Upon a suitable base or board A which is secured to the wall-plate B are set holders C (five as shown) for the transmitters, preferably provided with screens C² to prevent the entrance of dust and other foreign matter. At the forward end of each transmitter is located a sound-receiving trumpet or tube D, D', the central trumpet D being straight, while the lateral trumpets D' are curved, so that they will converge forwardly. Adjacent to the point toward which the said sound-receiving tubes converge, we locate a guide K for positioning the operator's mouth, so that the sound waves will produce the maximum effect. This annular guide K is preferably adjustable, being for this purpose carried by a rod K' mounted to slide in a sleeve K² and secured in position after adjustment by a set screw K³. We have found that with different persons the distance at which the ring K should be from the sound-receiving tubes D,

D', in order to secure the best results, is not the same, hence we have made provision for adjusting said ring as described. In order to better concentrate the sound waves, we may employ a sound shield or curtain L which should be extensible when the ring K is adjustable as described.

The transmitter proper may be of any suitable construction, although we prefer that shown in our application for a patent filed January 19, 1907, Serial No. 353,004, in which we have claimed certain features of the transmitter which we believe to be novel *per se*. The receiver (indicated diagrammatically at M) may likewise be of any approved construction, although we prefer a receiver provided with a curved amplifying horn R, and particularly the type disclosed in our application for a patent filed February 7, 1907, Serial No. 356,171.

The connections in which the transmitter and receiver, hereinbefore referred to, may be utilized are shown in Fig. 2. As illustrated in Fig. 2, wires 20, 20^a, 20^b, 20^c, 20^d are connected with one terminal of each of the transmitters D, D', the other terminals are connected by wires 21, 21^a, 21^b, 21^c, 21^d with switches Y from which a wire 22 leads to one pole of a battery 23. Suitable fuses T are interposed in the wires 21, 21^a, 21^b, 21^c, 21^d between the respective switches Y and the transmitters D, D'. The wire 20 is connected with two receivers (in series), 25^a being the wire connecting one receiver with the other, and wires 25, 24 complete the circuit by connection with the battery 23. From the wire 24 branch wires 25, 26, 27, 28 and 29 each lead to one of the receivers, and then wires 25^a, 26^a, 27^a, 28^a and 29^a connect with another receiver which also has a connection to the wire 20, 20^a, 20^b, 20^c and 20^d respectively. It will therefore be seen that each of the transmitters D or D' is in circuit with a plurality of receivers, two of them in the particular case illustrated. If, for instance, the switch Y, shown at the extreme left in Fig. 2, is thrown in, the circuit will be closed through the two receivers which are shown connected by the wire 25^a. The entire current of the battery 23 will pass through the said receivers, and owing to this fact, and also to the use of the amplifying horn R, the words spoken into the transmitter will be heard very distinctly even at a considerable distance from the receivers (par-

ticularly when employing the sensitive construction of both transmitter and receiver shown in our applications hereinbefore referred to). We therefore provide a very 5 loud-speaking telephone, and the advantage of such an arrangement will be understood by reference to a few examples of use. For instance, in a shop while the employees are at work at their various benches or machines, 10 any one of them can be called up and asked to report, say, at the office, and the signal will be heard by all employees who are within the room; or in a hotel a loud-speaking telephone of this character may be installed in 15 the café, and the clerk may, from the central station, send a message such as "Telegram for Mr. Smith"; or, "Mr. Jones is wanted at the office", and so on. Alarms of fire may also be sent in the same way very expeditiously. By throwing in two or more of the 20 switches Y, a greater number of transmitters and receivers will be included in the circuit. A multiple switch or the general switch, such as indicated by Z in Fig. 2, is provided which 25 is so constructed that a number of switches or all of them may be operated simultaneously. When wishing to send an alarm of fire, the clerk in the hotel, for instance, would operate the general switch Z, and then shout 30 his warning message into the transmitters, in which case the message would be heard in all the rooms in which loud-speaking receivers are installed.

We have shown the receivers in circuit 35 with the transmitters directly, but we desire it to be understood that the indirect connection by means of induction coils, which is well-known in telephony, may be used in connection with our invention, and where in 40 the claims we speak of elements of the apparatus being in circuit with each other, we desire it to be understood that this term is used in a sense broad enough to include an inductive relation.

In some cases it may be convenient to provide 45 means whereby a telephonic answer may be given to the operator at the central. In Fig. 2, a wire 30 is so arranged as to lead part of the current of the battery 23 to a transmitter X, located adjacent to one of the 50 receivers, and the other terminal of said transmitter is connected by a wire 31 with a receiver U, from which a wire 32 leads to a switch lever V normally kept down by hanging the receiver U on it in the customary 55 manner. The circuit is broken in this position, but when the receiver U is removed from the hook, the lever V swings upward under the influence of a spring and closes the circuit at 33 through a wire 34 connected with one terminal of the battery 23. The receiver U and transmitter X are not of the loud speaking variety and use only part of the current of the battery. 60

We claim as our invention: 65

In a telephone system, the combination of a common source of current, a conductor leading from one pole to a plurality of line terminals, a plurality of transmitter-circuits each having therein a transmitter, the transmitters being so grouped as to be simultaneously operated from the same source of sound, switches individual to the transmitter-circuits and capable of being operated singly or together, one or more receivers in 70 and individual to each transmitter-circuit, and a common conductor leading from the other pole of the battery or other source of current to the receiver-circuits. 75

In testimony whereof, we have signed our 80 names to this specification in the presence of two subscribing witnesses.

ADOLPH G. KAUFMAN.
LEOPOLD J. LIPPMANN.
